ELECTRIC TIME RELAY

Application filed December 27, 1927, Serial No. 242,882, and in Germany December 30, 1926.

Electric relays are frequently equipped with retarding devices which delay the time of closure and such retarding mechanism is usually interposed between the driving and the driven system of the relay. As, however, the retarding action is needed only on the working stroke of the relay the retarding mechanism is rendered inoperative on the return stroke by a coupling in the relay drive which is automatically disconnected on the relay returning into its initial position. The connection and disconnection of the coupling, however, requires a relatively great expenditure of force and has heretofore generally been effected by means of the same relay electromagnets which cause the relay to act.

According to the present invention the automatic coupling and uncoupling of the driving and the driven system of the relay is effected in such a manner that the work required for connecting and disconnecting the coupling is provided exclusively by the driving system, while the electric means feeding the relay has only to perform the tripping work.

The coupling may consist for instance of a motor driven wheel which drives at least one other wheel journaled in a rocking member coaxial with the said wheel, so that through the driving torque the rocking member is swung round and the wheel journaled in it is thereby caused to engage with or be disengaged from the other wheel belonging to the driven system.

In the accompanying drawing a time relay mechanism of this kind is shown in elevation Fig. 1, and plan view Fig. 2.

The motor or driving force for the time mechanism is the spring *a*, on the shaft *b* on which is mounted the toothed wheel *c* and which is wound up in the direction indicated by the arrow. The shaft *d* of the second set of wheels *e, f* is also journaled in the fixed frame *g* of the relay and supports the ratchet wheel *h* with which the detent *k*, which is pressed against it by the spring *z*, engages, when the relay magnet *i* is not energized or not sufficiently energized. Between the two stops *m* and *n* the frame *o* rocks about the shaft *d*, in which frame two further shafts,

namely the shafts *s* of the pair of wheels *p* and *q* and the shaft *t* of the wheel *r* are journaled, the latter shaft *t* also supporting the damping vane wheel *u*. Above the wheel *q* is journaled, also in the frame *g*, the driving wheel *v* with the cord pulley *w*, which, on the relay acting, winds up the weight *x* until it strikes against the contact apparatus *y*.

The relay acts, when through the electromagnet *i* being suitably energized, the detent *k* is disengaged from the ratchet wheel *h*. The spring *a* will then drive the train of wheels *c, e, f, p, q, r* which is damped by the air resistance of the vane wheel *u*, the direction of rotation of the various shafts being indicated by arrows. On the locking means *h, h* being released, the whole of the torque of the relay *f* will in the first moment be used for accelerating the following wheels *p, q, r*, and the damping vane wheel *u*, thus acting at the same time on the rocking frame *o*, causing the latter to lift from the stop *m* and to bring the wheel *q* into engagement with the wheel *v*. These wheels remain in engagement until, through the magnetic circuit *i* being broken owing to contact being made at *y* or for some other reason, the detent *k* is again brought into engagement with the wheel *h* bringing the toothed wheel *f* to rest. Owing to its kinetic energy the wheel *q* will continue to rotate and through the counter balance moment thus created moves the rocking member *o* out of engagement, so that the weight *x* is free to descend and the relay is again ready for operation.

When the driving mechanism is so constructed as to be capable of being driven in both directions of rotation, it is possible to couple for each direction of rotation a separately driven system with the drive.

The invention is not limited to relays having a train of wheels, but is also applicable to friction wheel driven gears, cord driven gears or the like. In place of the spring motor, another motor of any kind may be used. The release mechanism may be different from that shown in the example illustrated, also the responding member and the retarding device. The latter may be connected to the

driven system instead of to the intermediate gear.

What I claim is:

1. A time relay mechanism comprising a motor disposed in a fixed frame, a plurality of gears in said frame driven by said motor, releasing and locking means for controlling the operation of said gears, a second frame oscillatable about said fixed frame, a plurality of gears disposed in said frame and adapted to be driven by the movement of the gears in the fixed frame, a gear wheel mounted in said fixed frame and adapted to be driven by one of the gear wheels of the oscillatable frame when the frame is moved from its normal position, upon the releasing of the driving motor, and means actuated by said gear for operating an electrical contact.
2. A time relay mechanism comprising a motor disposed in a fixed frame, a plurality of gears in said frame driven by said motor, releasing and locking means for controlling the operation of said gears, a second frame oscillatable about said fixed frame, a plurality of gears disposed in said frame and adapted to be driven by the movement of the gears in the fixed frame, a governor for controlling said gears, a gear wheel mounted in said fixed frame and adapted to be driven by one of the gear wheels of the oscillatable frame when the frame is moved from its normal position, upon the releasing of the driving motor, and means actuated by said gear for operating an electrical contact.
3. An electric time relay comprising a pair of contacts, a driving train of wheels actuated by an independent source of power, a tripping electromagnet controlling a detent for said driving train, a driven system of wheels which operates the said contacts after a predetermined time interval from the start of said driven system and an automatic coupling, energized by said source of power for connecting said driving and driven systems upon release of said detent, said coupling including a planet wheel mounted in a pivoted frame.

In testimony whereof I have signed my name to this specification.

JOSEF STOECKLIN.
